(57) **CLAIM**

The ornamental design for a combination detachable heel support and protector, as shown and described.

DESCRIPTION

FIG. 1 is a left side view of the combination detachable heel support and protector, showing my new design;

FIG. 2 is a right side view thereof;

FIG. 3 is a front view thereof;

FIG. 4 is a rear end view thereof;

FIG. 5 is a top view thereof;

FIG. 6 is a bottom view thereof;

FIG. 7 is a top perspective view thereof; and,

FIG. 8 is a top perspective view combination detachable heel support and protector in an open position.

The broken lines illustrate environmental structure and form no part of the claimed design.
